UNITED STATES PATENT OFFICE.

CHARLES DE LOS RICE, OF HARTFORD, CONNECTICUT.

MULTIPLE-SPINDLE MILLING-MACHINE AND THE LIKE.

1,215,705.

Specification of Letters Patent. Patented Feb. 13, 1917.

Application filed June 17, 1913. Serial No. 774,123.

To all whom it may concern:

Be it known that I, CHARLES DE LOS RICE, a citizen of the United States, and a resident of Hartford, in the county of Hartford and State of Connecticut, have invented 5 certain new and useful Improvements in Multiple-Spindle Milling-Machines and the like, of which the following is a specification.

10 The inventions herein illustrated and described relate generally to improvements designed to facilitate manufacturing operations and to reduce the cost of production of various devices or their parts.

15 Generally speaking, it has been my purpose to group together on a single frame a plurality of operating mechanisms adapted to perform like or similar operations, provide these mechanisms with a common driving 20 means, provide a common feed of the work relatively to the operating means, and an automatic return and stop device acting both on the operating mechanism and on the feed to stop moving parts of the machine 25 and its elements when the work has been accomplished and the parts returned to starting position. By so arranging and organizing a machine as will be hereinafter more particularly described, and by carefully 30 figuring feeds and speeds and the number of the operating mechanisms (tools) which shall be utilized, it is possible to group two like machines opposite one another front to front operated by one workman, the feed 35 and speed of one machine being such as to give the workman time to first unload, and then reload the other machine and set it into operation before or at about the time the first machine has come to a condition of 40 rest. Thus, assuming that each machine is equipped, for instance, with four spindles adapted to carry milling cutters of various shapes and sizes, a single operative would be able to handle eight spindles, and between 45 the two machines maintain a continuous manufacturing operation. These results are made possible by the novel and advantageous construction and arrangement of the machines which will now be described 50 more in detail.

In order to make it possible to arrive at the results above outlined it has been necessary to provide an extremely compact arrangement of the machine, to make it automatic in its 55 operation except for the loading and unloading, and to simplify to the utmost all of the operations which the operative must per-

form. This has necessitated substantial departures from prior machine tool designs in the respects which will now be more particularly described and subsequently pointed out in the claims. And since the various devices forming the subject matter of the invention can be more clearly and simply described with reference to a concrete embodiment, the various features have been illustrated as incorporated in a multiple spindle milling machine.

Figure 1 is a front view of a machine embodying my invention.

Fig. 2 is an end view thereof.

Fig. 3 is a sectional end view.

Fig. 4 is a detail section of the table slide oiling device.

Fig. 5 is a detail sectional front view of 75 the same.

Fig. 6 is a detail view of the feed shaft driving connection.

Fig. 7 is an end view of the same.

Fig. 8 is a detail side view of a vise.

Fig. 9 is a plan view thereof.

Fig. 10 is a detail view from the rear, in section, of a portion of the main shaft and one spindle.

Fig. 11 is a rear view showing the frictional driving connection for the feed shaft, with parts shown in section.

Fig. 12 is a front view of one of the front housings.

Fig. 13 is a plan view thereof.

Fig. 14 is a side view, and Fig. 15 is a sectional plan view of the vise stem binder.

Fig. 16 is a detail view of the vise locator.

Fig. 17 is a detail elevation of the countershaft, showing the starting and stopping 95 connections with the machine.

Fig. 18 is a view looking from under Fig. 17.

A denotes the bed of the machine, the top of which is transversely channeled as at B 100 to receive the spindle housings. The spindles C, four of which are shown, extend transversely of the machine, that is to say, from front to back, and are supported in front and rear housings, the bed being transversely channeled to provide a secure seat for these housings and in which they are closely fitted. The front housings, indicated at a' , a^2 , a^3 , and a^4 , are intended to slide in the channels to effect the adjustment 110 of the spindle and its tool relative to the work, being held down in place by gibs a^5 secured to the bed as by bolts a^6 . The spindles are shouldered near the front end as at

a⁸, to take a bearing against the front of the front housing, and are threaded where they emerge from the rear of these housings to take a thrust collar *a⁹* and adjusting nuts *a¹⁰*. The spindle of course is mounted in a suitable bushing in this housing. When the spindles and their front housings are properly adjusted they are locked by the bolts *a¹¹*, which take into the bed. The 10 housings are slotted as at *a¹²* to receive these bolts and permit of adjustment.

The rear housings, *b*, *b'*, *b²*, and *b³*, are mounted in the channels of the bed and fixedly secured therein. Each of these housings has spindle bearings *b⁴*, *b⁵*, preferably of ball-bearing or other anti-friction type, which are of course in alinement with the bearings in the front housings.

The front and rear spindle housings have 20 oppositely projecting tail pieces *a¹³*, *b⁷* respectively, in the ends of which are oppositely threaded holes to receive the oppositely threaded ends of adjusting screws *a²⁰*, having a central portion adapted to be operated by a wrench of some sort. The rear housings being fixed, the front housings can be adjusted by means of these screws and then locked in adjusted position by the bolts *a¹¹*.

30 Underneath the spindle bearings in the rear housings and arranged at right angles thereto are bearings *c'* for the main shaft *f*. Secured to each spindle within the rear housing is a worm wheel *d* keyed to the spindle and clamped by the binder *d'*, the end of the worm hub being split for this purpose. Retaining nuts for the bearings are threaded onto opposite ends of the worm hub adjacent to the bearings.

40 The main shaft *f* extends lengthwise of the machine and is supported in the bearings *c'*. Mounted on this shaft are the worms *g* adapted to mesh with the worm wheels *d* on the spindles. At one end of 45 the machine a step cone pulley *h* is secured to the main shaft, which may be belted up with any suitable source of power, as a countershaft, motor, or the like. This main shaft is the only member of the machine 50 driven from an outside source of power, the other moving parts of the machine taking their motion from it.

To the opposite end of this main shaft there is secured a friction disk *i*,—the plane 55 of whose face is substantially at right angles to the axis of the shaft and from which the power is transmitted through the friction wheel *j* and the friction wheel shaft *k* through the worm *l* through the worm 60 wheel *m* mounted on the feed shaft *n* and which carries the worm *n'* meshing with the worm wheel *o* on cam shaft *p* which extends from front to back of the machine supported in suitable bearings.

65 The main shaft has a suitable thrust-bear-

ing at its friction disk end to take the thrust of the friction wheel against the disk as indicated at *2^t*, and at its opposite end another thrust-bearing *3^t*, to take the thrust occasioned by the meshing of the worms and worm gears. 70

The means for holding the friction wheel *j* in proper driving contact with the friction disk *i* on the main shaft comprise a collar 60 encircling the upper end of the friction wheel shaft *k*, which is supported in a suitable anti-friction bearing, and this collar has a lateral extension 61, into which an end of a tension pull rod 62 is pinned, the other end of which passes through a boss 63 on the rear housing *b³*. This rod is supported in a sleeve 64 having a drive fit in the bore of the boss, and a spring 65 surrounds the rod bearing against the end of this sleeve, and having bearing against its opposite end a washer and a nut which is threaded onto the rod. By means of this nut the tension of the spring can be varied, and so vary the force with which the friction wheel *j* is drawn against the face of the friction 85 disk *i*. A friction relief nut 66 is threaded onto the pull rod 62 between the end of the sleeve 64 and the collar 60, in order that the frictional contact of the friction wheel *j* on the disk *i* may be released during the adjustment of the former to change the feed speed. 90 67 denotes a guard for the friction wheel, mounted in a boss 68 on one of the gibs *a⁵*, which holds the right hand front spindle housing in place. 95

At the front of the bed is a longitudinally arranged table slide I of dove-tail shape, the face of the slide being vertical and extending longitudinally of the machine, and it has a slight central longitudinal depression 2 to 105 reduce the contact area between it and the table and yet provide for a proper support for the table to give it the necessary rigidity. The table 10 has on its underside a downwardly extending apron 11 having an angular groove 12 at its upper rear part to accurately fit the upper edge of the table slide I. To the lower end of the apron there is secured a gib 13 angularly disposed to fit against the rear face of the lower edge 110 of the table slide, and it will be seen that there is thus provided a dove-tail groove in the rear of the table apron which fits accurately the dove-tail table slide on the bed, and on which the table is reciprocated 115 longitudinally of the machine to move the work supported thereon back and forth under the spindle tools.

The method adopted for lubricating the ways on which the table slides is as follows: 120 At suitably spaced intervals along the upper edge of the dove-tail table slide or ways, pockets 3 are formed, at one end of which is mounted a stud 4 having a yoke 5 loosely pivoted on the top thereof, which extends 125 130

over the pocket and supports an oil-distributing wheel 6 of such a diameter and so placed that it extends down into the pocket a suitable distance to dip into oil which is 5 contained therein and into contact with the groove in the table, with the result that as the table moves on the ways this distributing wheel is turned, furnishing a constant supply of oil to the ways. This yoke 5 is 10 pressed upwardly by a spring, and the stud 4 is loosely fitted to allow a slight swiveling action so that it will find and contact with both walls of the groove in the table and so effectually lubricate each. The oil supply 15 to the pockets is maintained in the following manner: The face of the table slide is longitudinally grooved at a point opposite the lower end of the pockets, and in this groove a brass tube 7 is forced, and up- 20 turned at one end, the other end being plugged so as to permit of draining and cleaning the oil pockets. Opposite each pocket a hole is drilled through the tube and face of the slide into the pockets, and 25 into this hole there is forced a tapered pin 8 having a longitudinal bore and an intercepting cross-opening forming communicating passages between the tube and the pockets. The oil level in the pockets can thus 30 be maintained at the proper point by keeping the tube with its turned-up ends filled to the corresponding level.

At the front of the apron 11 of the table 10 is a support 14 for a roller 15 which is 35 located in operative relation with the cam 16 on the cam shaft p , so that as the cam revolves in engagement with this roller the table is shifted to the right, as seen in Fig. 1 of the drawings. A spring 17 anchored 40 at one end in the bed, as indicated at 18, has its opposite end connected with the table apron as at 19. As the cam moves the table in one direction this spring is extended until the high point of the cam is passed, after 45 which the spring returns the table to normal position, always keeping the roller against the face of the cam.

The friction wheel shaft is connected with the feed shaft by a worm l and worm wheel 50 m , the latter of which is mounted on the feed shaft, it having a taper bore to fit the tapered end of the feed shaft, and is held in place by the hand-operable binder r which is locked by the nut s . By loosening the 55 lock nut and unscrewing the binder, the worm wheel may be disconnected from the feed shaft. This disconnects the power feed for the table and makes it possible to move the table by hand under the spindle tools 60 while the machine is being set up and the work and tools adjusted for the proper cut.

The means which I have provided for moving the table by hand comprises a bracket 20 secured to an end of the table, 65 bored and threaded to receive an adjust-

ing screw 21 an end of which is located in a recess 22 in the pedestal and supported by an anti-friction thrust-bearing. The outer end of the screw is properly shaped to receive an operating handle or wrench. By 70 this means the table can be moved under the work to accurately determine and fix the cut which the spindle tool will make, and when this is properly adjusted the power feed can be thrown into play by tightening up on the binder r , which forces the worm wheel m onto the feed shaft and establishes a driving connection. The spring returns the table to starting position. 75

Keeping in mind the necessity of so organizing all parts of the machine that they can be operated with the greatest convenience to the workman, it has been necessary to provide a novel work-holding device, especially for those cases where the cut is 80 across the piece rather than lengthwise of it. This has been necessary in order that the operating handle of the vise shall be at the front of the machine convenient to the operator while the movement of the vise 85 jaws or of the movable vise jaw is in a direction lengthwise of the table. In providing for such an arrangement of the parts I have produced a novel form of vise which 90 will now be described, it being understood 95 that there are as many vises as there are tool spindles.

On the front of the apron of the table are tubular hubs 30, to receive the cylindrical stem 31 of the vise, the stem projecting 100 through the hub to be engaged by an adjusting screw 32 mounted in a bracket 33 on the apron, and by means of which the vise as a whole may be raised or lowered, the adjusting screw bracket being split and provided with a clamp bolt 34 by means of which the adjusting screw can be locked in position after the vise is properly adjusted. For convenience in securing an accurate and fine adjustment of the vise a collar 35 is 105 located against the head of the adjusting screw having circumferential graduations, and a pin 36 secured in the bracket has its end overlying these graduations. For locking the vise in position the hub is transversely apertured at top and bottom just at the side of the longitudinal bore but so arranged that the aperture opens into the bore, as clearly indicated at 37, 38. In each of these apertures is located a pair of binders, 39, 40, the opposing ends of which at the side next the stem are oppositely inclined so that as these binders are drawn together they wedge against the vise stem. One of these binders, 40, is tubular to receive 110 a bolt 41, the threaded end of which engages a threaded aperture in the other binder 39. The squared end 42 of the bolt provides means for drawing together the binders 39, 40, longitudinally in the aper- 115

ture. The squared end 42 of the bolt provides means for drawing together the binders 39, 40, longitudinally in the aper- 120

ture to effect the clamping action on the stem.

In order to properly locate the vise, to insure the correct alinement of the clamping jaws with respect to the spindle and in parallelism therewith, I provide a cylindrical bushing 45 secured to the table as by the bolt 46, the head of which fits in one of the T slots 47 and which has at its other end a binding nut 48. Each vise body has a rectangular notch of such size as to receive this bushing and the bushing has a large bore so that it may move to always find a bearing against both walls of the notch.

15. The faces of the vise jaws extend transversely of the bed, at least one of the jaws being movable toward and away from the other to provide for clamping the work in position. Secured to the front part of the 20 vise body on the upper surface thereof is a vise-screw bearing 50 to support a vise screw 51, the threaded end of which is in engagement with a vise screw nut 52, which may be reciprocated on the vise body by the vise 25 screw. The vise body is provided with ways 53 upon which slides the movable jaw block 54, which is connected with the vise screw nut by a toggle link 55. It will thus be seen that by rotating the screw the nut is moved 30 transversely of the vise body, and through the toggle link the jaw block is moved longitudinally of the body toward and away from the stationary jaw 56.

The capacity of the vise depends upon the 35 length of the toggle link, various lengths of which are provided, and by this simple and advantageous arrangement the operating crank for the screw is located at the front of the machine, and the movable jaw block 40 can be readily and quickly actuated for the loading and unloading of the vise.

The starting and stopping of the machine is accomplished in the following manner: A foot treadle 80 has a front branch extending lengthwise of the machine, and rearwardly extending side arms which fit into brackets 81, 82, mounted on the bed. To one of these side arms is attached a connection with a belt-shifting arrangement at 50 the overhead countershaft, so arranged that when the treadle is pressed down the bell crank lever 104 is moved by the rod 105 to shift the shipper rod 103 which throws in the clutch pulley 101 to drive the cone pulley 100 which is belted down to the machine. The left-hand bracket 81 has a transversely arranged hub 83 in which is mounted a catch-pin 84 which is adapted to coöperate with a retaining pin 85 mounted in the lower 55 end of a retaining lever 86 to hold the foot treadle in its depressed position, and thus maintain the driving relation between the countershaft and the driving shaft of the machine. This retaining lever is pivotally

supported on the pedestal at a point substantially midway between its ends.

To the upper end of this retaining lever two connecting rods—90, 91—are attached, one of which, 90, extends to an emergency stop treadle 92, the other connecting rod—70 91—being connected to a downwardly extending lever 93 fast on one end of a rock shaft 94, to the other end of which is secured an upstanding release lever 95, the end of 75 which is in operative relation with one end of a longitudinally movable stop pin 96 suitably supported on the bed with its opposite end in operative relation with the cam 16. A spring 97 can be placed at any convenient point to hold the retaining lever and the rock shaft in normal position, that is to say, in the position where the retaining pin 85 at the lower end of the retaining lever 86 will interlock with the catch pin 84 on the bracket 81, and the release lever 95 in a position to be 80 actuated by the stop pin 96 when it is moved longitudinally by the knock-off pin 98 fixed in the side of the cam.

Suitable means is also provided, as a spring 87, to raise the foot treadle 80 when 90 it is released through the action of the cam by the disengagement of the retaining pin 85 from the catch pin 84.

It will be understood that the cam is timed to feed the table at the proper speed under the spindles and to permit of the spring 95 returning the table to its starting position, and different cams can be provided for different classes of work or to meet any peculiar conditions. These cams are fitted to 100 the tapered end of the cam shaft and locked by a nut. The knock-off pin is always in the same position relative to the stop face of each cam, and thus readjustment upon the substitution of a different cam is avoided. 105

Assuming now that the machine is at rest and the vises all filled with work to be operated on, a pressure of the foot treadle will depress it and the spring 97 will draw the retaining lever to a position to cause the retaining pin to interlock with the catch pin, and at the same time the drive for the main shaft is made effective. Power is delivered to the main shaft *f*, causing the spindle to rotate; thence through the friction disk *i* and friction wheel *j* to the friction shaft *k*; thence through the worm wheel *m* and worm gear *l* to the feed shaft *n*; thence through the worm *n'* and worm wheel *o* to the cam shaft *p*, causing the cam 16 to rotate. The 110 cam engages a roller 15 mounted in the table and drives the table to the right, carrying the work under the tools mounted on the rotating spindles. Each vise moves under but one spindle, and the tools of each spindle operate only on the parts held in one vise.

When the table has reached the limit of

its motion in this direction, the spring 17, which has been extended, draws the table back to its starting position, the rapidity of this motion being controlled by the cam, and at the time when the table reaches its starting position the knock-off pin in the cam moves the stop pin 96 longitudinally so that it engages the release lever 95, rocks the rock shaft 94, which through the connecting rod 91 moves the retaining lever 86 to disengage the retaining pin 85 from the catch pin 84 when the spring 87 raises the foot treadle interrupting the main shaft drive.

The main shaft drive is controlled as follows:—

The countershaft is equipped with a cone pulley 100 which is belted up with the cone pulley on the main shaft of the machine. It is also provided with a clutch pulley 101, the movable member of which is connected by a lever 102 with a shipper rod 103, and this shipper rod is moved longitudinally by a bell crank lever 104 which is connected through a connecting rod 105 with the foot treadle. On the countershaft there is a friction disk 106, a fixed brake shoe 107 at one side of this disk, and another brake shoe 108 mounted on and movable with the shipper rod.

When the table has returned to its position of rest, the knock-off pin on the cam moves the stop pin longitudinally, causing the shaft 94 to rock, disengaging the retaining pin 85 from the catch pin 84 when a spring 87 connected with the bell crank lever 104 shifts the shipper rod to disconnect the clutch pulley, and causes the friction disk to be engaged by the brake shoes to quickly stop the rotation of the countershaft; and consequently all moving parts of the machine.

A suitable work-oiling system is provided according to well known ideas, adapted for the particular purpose in hand.

Above the spindles a work-holding table is supported in a position convenient to the operator, and it may be conveniently supported on extensions from a suitable number of the studs which hold the gibs in place, as indicated at 110, 111, in the drawings.

I claim as my invention:

1. In a machine of the character described, a bed, a rotating tool-carrying element, arranged transversely of the bed, a longitudinally movable work-holding element, a feed and return mechanism therefor, a main shaft mounted on the bed, driving means therefor, driving connections between said main shaft and said tool-carrying and work-holding elements, means for starting said main shaft, and means for automatically stopping said main shaft.

2. In a machine of the character described, a bed, a rotating tool-carrying element arranged transversely of the bed, a longitudi-

nally movable work-holding element, a feed and return mechanism therefor, a main shaft mounted on the bed, driving means therefor normally inoperative, driving connections between said main shaft and said tool-carrying and work-holding elements, a latch mechanism for said main shaft drive when in operative position, and a trip mechanism in said feed and return mechanism co-operating with said latch mechanism to disconnect and stop the main shaft drive at the end of each complete movement of said feed and return mechanism.

3. In a machine of the character described, a bed, a rotary tool-carrying spindle arranged transversely of the bed and supported in suitable bearings, a table slide at the front of the bed extending longitudinally thereof under the spindle, a table mounted for movement on said slide, a work-holder located on said table, a main shaft supported in bearings on the bed, driving connections between said shaft and spindle, a feed and return mechanism for said table, driving connections between said main shaft and said mechanism, and automatically operating means for stopping said spindle and said table at the end of the return motion of the latter.

4. In a machine of the character described, a bed, a rotary tool-carrying spindle arranged transversely of the bed and supported in suitable bearings, a table slide at the front of the bed extending longitudinally thereof under the spindle, a table mounted for movement on said slide, a work-holder located on said table, feed and return mechanism for said table, a common driving shaft for said spindle and table supported in suitable bearings on said bed, and automatically operating means for stopping said driving shaft at the end of each return motion of the table.

5. In a machine of the character described, a bed, a rotary tool-carrying spindle arranged transversely of the bed and supported in suitable bearings, a table supported on and movable longitudinally of the bed underneath the spindle, a work holder mounted on the table, means for moving said table to carry said holder under and by said spindle, means for returning the table to normal position, a common drive for said spindle and table-operating mechanism, and means for disconnecting said drive from the spindle and table each time the latter returns to normal position.

6. In a machine of the character described, a bed, a rotating tool-carrying element arranged transversely of the bed, a longitudinally movable work-holding element, a feed and return mechanism therefor, a main shaft mounted on the bed, driving means therefor normally inoperative, driving connections between said main shaft and said

- tool-carrying and work-holding elements, a latch mechanism for said main shaft drive when in operative position, a trip mechanism in said feed and return mechanism co-operating with said latch mechanism to disconnect the main shaft drive at the end of each complete movement of said feed and return mechanism, and manually operable means for disconnecting said main shaft 5 drive independently of said trip mechanism.
7. In a machine of the character described, a bed, a spindle arranged transversely of the bed, a table adapted for reciprocating movement under the spindle, a work-holder mounted on the table, a main shaft supported in suitable bearings on the bed, geared driving connections between the main shaft and the spindle, a feed shaft for the table, an intermediate shaft having 15 geared connection with the feed shaft and frictional driving connection with the main shaft, and means for adjusting the contact pressure between said frictional driving members.
8. In a machine of the character described, a bed provided with a plurality of transverse channels in the top thereof, a pair of housings in each channel, means for fixedly securing one housing to the bed, 20 means for adjusting the other housing from the fixed housing, and means for locking the adjustable housing in position.
9. In a machine of the character described, a bed having a plurality of transverse channels in the top thereof, a pair of housings located in each channel at the front and rear ends thereof, the rear end housing being fast, the front end housing being adjustable, alined bearings in the rear 25 housings, a main shaft extending longitudinally of the machine and supported in said bearings, alined bearings in each pair of housings, spindles supported in said bearings and arranged at right angles to said 30 shaft, gear connections between said main shaft and said spindles located within the rear housing, a shoulder on each spindle in front of the front housing and having a bearing thereagainst, a lock collar on the 35 spindle at the rear of the front housing, and means for adjusting said front housings to move the spindles longitudinally.
10. In a machine of the character described, a bed, a main drive shaft mounted 40 thereon extending longitudinally thereof, a transversely arranged spindle having driving connection with said shaft, a longitudinally movable table, means for feeding said table under the spindle, driving connections 45 between the main shaft and said means, means for returning the table to normal 50

position, a shipper-rod by means of which said main shaft is connected with a source of power, a latch for maintaining this connection, a knock-off pin operatively engaged 65 with said latch, and means operable upon the return of the table to normal position for actuating said knock-off pin to disconnect said main shaft from its source of power.

11. In a machine of the character described, a bed, a main drive shaft mounted thereon extending longitudinally thereof, a transversely arranged spindle having driving connection with said shaft, a longitudinally movable table, means for feeding said table under the spindle, driving connections 70 between the main shaft and said means, means for returning the table to normal position, a shipper-rod by means of which said main shaft is connected with a source of power, a latch for maintaining this connection, a knock-off pin operatively engaged 75 with said latch, means operable upon the return of the table to normal position for actuating said knock-off pin to disconnect said main shaft from its source of power, and a foot lever for operating said latch independently of said means.

12. In a machine of the character described, a bed, a dove-tail slide arranged longitudinally at the front thereof, the face of said slide being vertically arranged, the table having a depending apron grooved at the rear to fit over the upper edge of said 90 slide, a gib removably secured to the lower edge of said apron and engaging the rear of the lower edge of the slide.

13. In a machine of the character described, the combination with a bed, a plurality of spindles arranged side by side transversely of the bed, a table slide and a table mounted for reciprocation thereon, of a plurality of work-holders mounted upon said table, one for each spindle, and means 100 for adjusting said work holders relative to said spindles independently of one another.

14. In a machine of the character described, a bed, a rotating tool-carrying element, a longitudinally movable work-holding element, a feed and return mechanism for the latter, a main shaft mounted on the bed, driving means therefor, driving connections between said main shaft and said tool-carrying and work-holding elements, 110 means for starting said main shaft, and means in said feed and return mechanism for automatically stopping said main shaft.
